UNITED STATES PATENT OFFICE.

EDWARD L. KNOWLES, OF ALLIANCE, OHIO.

DESIGN FOR A FLOWER-HOLDER.

57,843.

Specification for Design.

Patented May 10, 1921.

Application filed August 9, 1920. Serial No. 402,431. Term of patent 14 years.

To all whom it may concern:

Be it known that I, EDWARD L. KNOWLES, a citizen of the United States, residing at Alliance, in the county of Stark and State of Ohio, have invented a new, original, and ornamental Design for a Flower-Holder, of which the following is a specification, reference being had to the accompanying drawings, forming a part thereof.

The figure is a perspective view showing my new design.

I claim:

The ornamental design for a flower holder, as shown.

EDWARD L. KNOWLES.
